CLAIM

The ornamental design for a catheter flush flow control device, as shown.

DESCRIPTION

FIG. 1 is a perspective view of a catheter flush flow control device showing my new design.

FIG. 2 is a side view of the controller shown in FIG. 1.

FIG. 3 is a top view of the controller shown in FIG. 1.

FIG. 4 is a bottom view of the controller shown in FIG.

1.

FIG. 5 is a front view of the controller shown in FIG.

1.

FIG. 6 is a rear view of the controller shown in FIG. 1.
